(57) **CLAIM**

The ornamental design for a pocket combination turkey call, as shown and described.

DESCRIPTION

FIG. 1 is a perspective view of a pocket combination turkey call showing my new design.

FIG. 2 is a right side view thereof.

FIG. 3 is a front view thereof.

FIG. 4 is a rear view thereof.

FIG. 5 is a top view thereof.

FIG. 6 is a left side view thereof; and,

FIG. 7 is a perspective view thereof showing the striker thereof positioned alongside the box of the call.

The bottom of the pocket combination turkey call is flat and unadorned.
